Patented Oct. 17, 1916.

UNITED STATES PATENT OFFICE.

CARL MORU, OF KENOSHA, WISCONSIN, ASSIGNOR TO THE BADGER BRASS MFG. CO., OF KENOSHA, WISCONSIN, A CORPORATION OF WISCONSIN.

UNIVERSAL CLAMP.

1,201,330.

Specification of Letters Patent. Patented Oct. 17, 1916.

Application filed January 7, 1916. Serial No. 70,727.

To all whom it may concern:

Be it known that I, CARL MORU, a citizen of the United States, and a resident of Kenosha, in the county of Kenosha and State of Wisconsin, have invented certain new and useful Improvements in Universal Clamps, 5 of which the following is a specification.

My invention relates to improvements in universal clamps, and is particularly well fitted for use where it is desired to support a device or instrumentality in such a manner that it may be adjusted to occupy any relative angular position with respect to its support.

Among the salient objects of the invention are, to provide a universal clamp of the type referred to in which the device to be supported may be rotated or adjusted about a pair of axes arranged at an angle to each other; to provide a construction so arranged that the clamp may be locked securely in its adjusted position by manipulating a single part; to provide in a construction which includes a common member rotatably related to a pair of independent members arranged on relatively inclined axes, a single locking member the manipulation of which clamps both of said parts against their respective rotary movements; to provide in a construction of the type last described an arrangement such that the independent members may be frictionally held in such a manner as to permit of adjustment of the device supported while at the same time no manipulation of the locking member is necessary to enable the device to maintain its adjusted position; to provide a compound frictional clamp of the class described so organized that the manipulation of a single locking member results in a substantially equal amount of tightening or loosening of the parts in each of their respective rotary movements; to provide a clamp of the class described so organized that movement of the device with respect to its support will not result in tightening or loosening of the clamping means; to provide a construction which may be so adjusted that it will retain its adjusted position indefinitely though subjected to severe shocks or vibration; to provide a construction which shall be neat and graceful in appearance, efficient, convenient in its manipulation, simple in design, economical to manufacture and maintain; and, in general, to provide an im-

proved universal clamp of the character referred to.

In this specification I will describe the application of my invention to a clamp used for supporting an electric search lamp on 60 a self-propelled vehicle, by aid of the accompanying drawings, in which—

Figure 1 shows a preferred form of clamp adjustably supporting the search lamp; Fig. 2 is a plan view of Fig. 1, showing the clamp only; Fig. 3 is a section taken on the line 3—3 of Fig. 2; and Fig. 4 is a section taken on the line 4—4 of Fig. 3.

Referring to the drawings, 10 represents fragmentarily a vertical rod, such as a wind-shield part, upon which it is desired to support adjustably the hand-electric search lamp 11. The search lamp is an ordinary electrically operated automobile lamp of the parabolic type, which need not be specifically described, since the details thereof form no part of my invention.

The clamp in its preferred form is mounted upon a horizontal arm or rod 12 which is secured to the wind-shield member 10 by means of a pair of opposed jaws 13 and 14 partially embracing the vertical rod 10 and preferably lined with felt 15 in order to avoid marring the finish of the wind-shield. The movable jaw 14 is forced toward the jaw 13, which is integral with the horizontal part 12, by means of a pair of spaced apart clamping screws 16. The rod 12 constitutes the fixed member of the clamp and is intended to be permanently stationary 85 with respect to the wind-shield member 10. Referring to Fig. 3, it will be observed that the outer end of said horizontal stationary rod 12 is reduced in its diameter so as to constitute a cylindrical stem 17 which fits within a cylindrical longitudinal hole drilled in the common clamping member 18. Said common clamping member 18 is sawed out longitudinally or axially, as shown at 19 in Fig. 1, to a sufficient distance along its axis to impart a considerable amount of resiliency to the outer forked ends 20 and 21. Through the outer end of the common clamping member 18, and substantially at right angles to the plane of the sawed kerf 19, I drill a transverse cylindrical aperture which admits freely the threads of the clamping screw 22. The threads of said clamping screw 22 are turned off for some distance from one end of the screw, the end 110

23 so reduced being inserted in the neck piece 24. The screw 22 is securely fixed against all movement in the neck piece 24 by a taper pin 25 driven through both of 5 said parts. The neck piece 24 forms the outer or movable member of the clamp supporting the lamp, which is rigidly secured to the neck piece by means of an integral flange 26 and rivets 27. Both ends of the 10 transverse hole through the common clamping member 18 are countersunk conically, as shown in Fig. 3, the outer end of the neck piece 24 being similarly turned off to fit into one of said countersinks. Within the other 15 countersink is rotatably seated a sliding cone-shaped collar 28 which may be forced into its seat by means of the wing-nut 29 threaded upon the outer projecting end of the screw 22.

20 In order to prevent removal and possible loss of the wing-nut 29 and at the same time prevent theft of the lamp, the extreme outer end 30 of the screw 22 is left of its original diameter and is unthreaded. Along the outer 25 side of the screw 22 I mill a key-way 31, and when making the conical washer 28 the central hole is punched out into the shape indicated in Fig. 4, the inwardly projecting tip 32 so formed being of the proper width and 30 depth to enter and slide freely within the key-way 31, thus preventing the washer 28 from turning upon the screw 22 when the wing-nut 29 is manipulated. In order to prevent the common clamp member 18 from 35 working off the reduced cylindrical end 17 of the stem piece 12, I turn in the outer end of the latter a circumferential groove 33 within which fits the end of the short round pin 34 seated in an aperture drilled transversely in the outer face of the fork 20. Loss of said small pin 34 is prevented by 40 drilling said hole close enough to the axis of the screw 22 to bring the outer end of said pin 34 within the area of the inner face of 45 the wing-nut 29.

The construction described is remarkably simple in its details and exceptionally easy and convenient to manipulate. The longitudinal cylindrical hole in the common 50 clamping member 18 is drilled to such diameter that the reduced end 17 of the rod 12 rotates freely within said hole when the wing-nut 29 is unscrewed. When, however, the clamping nut 29 is screwed up, the forks 55 20 and 21 are squeezed together and at their inner ends tightly grasp the cylindrical end 17 of the rod 12 and prevent relative rotary movement of the clamping member 18 around the part 12. The setting up of the 60 nut 29 at the same time forces the conical washer 28 tightly into engagement with the countersink in the outer face of the forked part 20, and also forces the conical end of the neck piece 24 into frictional gripping 65 engagement with the countersink in the

outer face of the forked member 21. Since the screw 22 is rigidly secured in the neck piece 24 by means of the pin 25, while the conical washer 28 is keyed to said screw 22 by the key-way 31 and tongue 32, the common clamping member 18 is forced into frictional engagement with the neck piece 24. When the wing-nut 29 is tightened sufficiently, both of the parts 12 and 24 are locked absolutely against rotary movement 70 respectively in the common clamping member 18. If, however, it be desired to adjust the lamp or other device into a different angular position with respect to the stationary member 12, the nut 29 is released sufficiently to allow said parts 12 and 24 to rotate with respect to the common clamping member 18.

I preferably proportion the areas of the various frictional gripping surfaces and the 85 inclination of the cones so that the tightening of the common clamping member 18 will tighten the two rotary joints a substantially equal amount. This enables me to adjust the nut 29 in such position that the lamp or other device may be moved about both axes of rotation with a substantially equal amount of torsional force, each joint having equal tightness. When the wing-nut 29 is properly adjusted, the lamp may, 90 by the exercise of a reasonable amount of manual strength, be swung or adjusted in either or both directions of rotary movement and will maintain its adjustment in whatever angular position it may be placed. This is a great convenience in a universal clamp when employed for a purpose such as I have described, since there is no need to manipulate the clamping nut whenever it becomes necessary to adjust the lamp. It will be observed that when moving the lamp around its vertical axis, there is no tendency to rotate the nut 29 on the screw 22 on account of the fact that the conical washer 28 is keyed to said screw. A construction which admits 95 of such an arrangement possesses great merit for that reason alone.

In view of the fact that the described details of construction may, without loss of efficiency, be modified to suit individual 115 needs, the scope of the invention must be determined by reference to the appended claims.

I claim:

1. In a universal clamp, the combination 120 of a relatively fixed circular stem, a common clamping member rotatable upon said stem and having a pair of opposed gripping surfaces embracing said stem, a relatively adjustable extension member rotatably arranged with respect to said common clamping member about an axis angularly disposed with reference to said first rotary axis and having a gripping surface engaging said clamp, and a screw passing through 125

- said clamp and arranged to force said extension into gripping engagement with said clamp and simultaneously to force said opposed gripping surfaces into clamping engagement with said stem whereby all of said parts are locked together.
2. In a universal clamp, the combination of a relatively fixed cylindrical stem piece, a common clamping member apertured to 10 rotate upon said stem, the opposed sides of the interior of said aperture being capable of movement toward or from each other, a third member rotatable on said common clamping member around an axis substantially at right angles to the axis of the stem, said third member and said common clamping member having cooperating frictional gripping surfaces, and a screw coaxial with the axis of rotation of said third member 15 passing through said common clamping member and adapted simultaneously to force said third member into gripping engagement with said common clamping member and said opposed gripping surfaces into clamping engagement with said stem.
3. In a universal clamp, the combination of a longitudinally split common clamping member longitudinally apertured at its end remote from the split, a stem piece having 20 a cylindrical end rotatably fitting within said aperture, said stem being positioned longitudinally within said aperture, the split end of said common clamping member being transversely apertured, a third member 25 rotatable upon said common clamping member about the axis of said transverse aperture and having circular gripping area coöperating with said common clamping member, a clamping screw passing freely 30 through said transverse aperture and rigidly secured at one end in said third member, and a wing-nut threaded upon the other end of said screw and adapted to force said common clamping member into engagement 35 with said third member.
4. In a universal clamp, the combination of a longitudinally split common clamping member longitudinally apertured at its end remote from the split, a stem piece having a 40 cylindrical end rotatably fitting within said aperture, said stem being positioned longitudinally within said aperture, the split end of said common clamping member being transversely apertured, a third member rotatable upon said common clamping member 45 about the axis of said transverse aperture and having circular gripping area coöperating with said common clamping member, a clamping screw passing freely through 50 said transverse aperture and rigidly secured
- at one end in said third member, a wing-nut threaded upon the other end of said screw and adapted to force said common clamping member into engagement with said third member, and a washer non-rotatable 55 upon said screw interposed between said wing-nut and said common clamping member.
5. In a universal clamp, the combination of a supporting stem having a cylindrical 60 end provided with a circumferential groove at its outer end, a common clamping member longitudinally apertured at its inner end to admit said cylindrical end, a pin carried by said common clamping member and having its end projecting within the groove of said stem to prevent end-wise movement of said stem in said aperture, said common clamping member being sawed axially at its outer end and provided with a transverse 65 cut and beyond the outer end of said stem, the outer ends of said aperture being enlarged, a third main member rotatably seated within one of said enlargements, a 70 screw passing through said transverse aperture and having one of its ends rigidly secured in said third main member, a wing-nut threaded upon the outer end of said screw, and a washer seated within the other 75 enlargement of said transverse hole interposed between said wing-nut and said common clamping member and keyed slidably upon said screw.
6. In a universal clamp, the combination of a relatively fixed cylindrical stem piece, a common clamping member rotatable upon 80 said stem and having opposed portions engaging and on opposite sides of said stem capable of movement toward each other to 85 grip said stem, a third member rotatable on said common clamping member around an axis substantially parallel with the direction of movement of said gripping portions and at right angles to the axis of said stem, said 90 third member and said common clamping member having coöperating frictional gripping surfaces concentric with the last named axis, and a screw coaxial with the axis of 95 rotation of said third member passing through said common clamping member and adapted simultaneously to force said third member into gripping engagement with said common clamping member and said opposed gripping portions into clamping engagement 100 with said stem, the end of said stem stopping short of said screw, the stem axis 105 intersecting the axis of the screw.

CARL MORU.
